UNITED STATES PATENT OFFICE.

PHILIP J. MEAHL, OF SUMMIT, NEW JERSEY.

MUSIC-RECORDER.

1,351,432.

Specification of Letters Patent. Patented Aug. 31, 1920.

Application filed March 27, 1919. Serial No. 285,496.

To all whom it may concern:

Be it known that I, PHILIP J. MEAHL, a citizen of the United States, residing at Summit, in the county of Union and State of New Jersey, have invented certain new and useful Improvements in Music-Recorders, of which the following is a specification.

My invention relates to apparatus for recording music on paper rolls by punching holes or slits in the paper at appropriately spaced intervals, the perforated paper rolls being adapted for use in piano players and the like in a well known manner. My present invention constitutes an improvement on the type of apparatus disclosed in my Patent No. 654,473, July 24, 1900, in which a plurality of horizontally arranged levers have punches secured thereto and are constantly vibrated in the horizontal plane during the operation of the machine. When a note is to be recorded as upon the striking of a key of a piano, the fulcrum of the lever, which is properly positioned for the recording of that particular note, is shifted downwardly to a slight extent. This causes the punch belonging to that lever to perforate the paper during its rapid up-and-down movements, so long as the lever is held in its shifted position. A difficulty which has been encountered in the use of this type of device consists in the fact that the punches tend to bind in their guides and to strike against the edges of the die openings below the paper, because of the fact that the levers are connected by rigid pivotal connections to the devices which cause their constant vibration. I have overcome this difficulty by a construction in which a rigid connection with the vibrating means is eliminated and a sliding or loose connection is substituted. Because of this arrangement the horizontal levers are enabled to adjust themselves slightly in relation to their actuating devices, and to thereby enable the punches to travel easily in their proper vertical paths without binding.

The objects of my invention are to improve the construction of apparatus of the character referred to in the manner described above, and to provide other improved details of construction and combinations of parts whereby the efficiency, reliability and accessibility of the machine will be increased.

In order that a clearer understanding of my invention may be had, attention is hereby directed to the accompanying drawings forming part of this application and illustrating one embodiment of my invention. 60 In the drawings Figure 1 represents a front elevation of an apparatus constructed in accordance with my invention, certain parts being shown broken away and certain parts being omitted for the sake of clearness; 65 Fig. 2 is a vertical section taken on line 2—2 of Fig. 1, a connection with a piano key being also indicated; Fig. 3 is a partial side elevation of the machine showing the paper feed drive; and Fig. 4 is a perspective 70 view showing one of the operating levers and its co-acting parts.

Referring to the drawings the apparatus is provided with a frame 1 having side portions 2, 2, and horizontal upper and lower 75 cross portions 3 and 4. A supplemental frame having side portions 5, 5, is secured upon the frame 1 as by providing the side portions 2, 2, of frame 1 with a suitable plurality of lugs 6, 6, upon which rest lugs 80 7, 7, which extend outwardly from the frame members 5, 5, these lugs being secured together by bolts 8 extending through the same.

In the form of construction illustrated a 85 motor 9 is mounted on the cross portion 4 of frame 1, this motor driving a pulley 10 by means of a belt 11, pulley 10 being mounted on one end of the stud shaft 12, which is supported in side frame members 90 5, 5.

Rotating with pulley 10 is a spur gear 13 which rotates two spur gears 14, 14, which are fast on eccentric shafts 15, 15.

Rotation of eccentric shafts 15, 15, causes 95 the rapid reciprocation of the pitmen 16, 16. These pitmen are pivotally connected at their lower ends by pins 17, 17, to a pair of horizontal bars or members 18, 18, which extend in parallel relation across the machine and are slidably mounted in vertical slideways in the upright frame members 5, 5. The members 18 are thus given a continuous rapid up-and-down movement of a limited extent during the operation of the 100 105 machine.

The punches 19 are pivotally connected at their upper ends to levers 20, 20, each of which corresponds to a desired note to be recorded. Each lever 20 is pivotally con- 110

5 nected at one end to a vertical member 21, members 21 being slidably mounted in guiding slots 22 which are arranged vertically in horizontal retaining bars 23, 23, which are mounted on the frame at opposite sides of the machine. The vertical members 21 are pivotally connected at their lower ends to the actuating levers 24, each of which is pivotally mounted, as shown at 25, to a 10 frame member 26. Springs 27 are each secured at one end to an outer or free end of a lever 24 and at their opposite ends to the frame members 26, so that the inner ends of levers 24 and also the outer ends of the levers 20 are normally held in a raised position.

20 The rapidly reciprocating members 18 are provided with a number of slots 28, 28 (best shown in Figs. 2 and 4), one for each of the levers 20. The ends of levers 20 opposite from their pivotal connections with vertical members 21 are provided with rounded enlargements 29 which are slidably positioned within these horizontal slots 28. Members 18 and levers 20 are balanced against overthrow by springs 30, 30, which are mounted between the lower surfaces of members 18 and lugs 31, 31, formed on frame members 5, and springs 32, 32, which are positioned between the upper surfaces of members 18 and lugs 33, 33, on frame members 5, 5. Punches 19 are slidably mounted in vertical openings 34 which extend through guide member 35. The punches are adapted to enter suitable openings in the die-plate 36 over which the paper roll passes, these openings being in alinement with the guide openings 34.

25 The levers 20 are preferably arranged to extend from opposite sides of the apparatus, as is shown, for the sake of compactness. A suitable number of these levers and connected parts may be employed, such for example as 44 levers 20, on each side. So long as no piano key is depressed the actuating levers 24 remain in their upper positions with the pivotal connections 37 between levers 20 and vertical members 21 acting as fixed fulcrums from which levers 20 oscillate. The opposite ends of levers 20 being rapidly reciprocated by their connections with members 18, the punches 19 will be given up-and-down movements insufficient in extent to cause the punches to touch the paper which runs over die 36. When, however, levers 24 are depressed upon the actuation of piano keys, the corresponding fulcrums 37 will be shifted or depressed to a sufficient extent to cause the corresponding punches to penetrate the paper and enter the openings in die 36 so long as the piano key or keys are depressed.

30 It will be noted that the sliding connections between the ends 29 of levers 20 and members 18 permit the free movement of punches 19 in their guides without cramp-

ing or getting out of alinement. This is because the ends 29 of levers 20 move slightly backward and forward in horizontal slots 28 as members 18 move up and down, in accordance with the divergence between the vertical straight line paths followed by members 18 and the slightly curved paths followed by the ends 29 of levers 20 as the levers oscillate about their pivotal points 37.

35 The paper to be perforated is indicated at 75 38 as passing from a roll 39 mounted on a bracket 40, thence passing over the die 36 and being wound up on a receiving roll 41 mounted on a bracket 42. The die 36 is preferably mounted on a sector 43 which is secured to a member 44 which is partially cylindrical, but is provided with a plane upper surface upon which the sector 43 is secured. Member 44 is also provided with a plane lower surface which is secured upon a bracket 45, which has two side portions 46 to which the guide member 35 is secured. The latter is shown as consisting of two horizontal portions which are spaced apart and secured together at opposite ends by spacing 80 blocks (not shown).

40 One of the eccentric shafts 15 is provided with a spur gear 47 which meshes with a spur gear 48, which turns freely on one end of the stationary spindle 12. A bevel gear 49 rotates with gear 48 and meshes with a bevel gear 50 on the end of a shaft 51 which is supported by a bracket 52. The opposite end of this shaft is provided with a worm 53 which rotates a worm wheel 54 on the end 100 of a shaft 55, a bracket 56 being provided to support the lower end of shaft 51. Shaft 55 extends through the center of the drum 44 which carries the sector 43 and die 36, shaft 55 being provided at opposite ends of 105 drum 44 with a pair of feed wheels 57, 57. These are provided with projections 58 which are adapted to enter perforations 59 in the paper strip 38, to feed the latter in the well known manner. The take-up roll 41 is 110 rotated from shaft 55 by a chain connection 60. The take-up roll 41 is adapted to be removed when filled by removal from its bearings in the usual manner.

45 The actuating levers 24 may be operated 115 by any desired means upon the operation of the piano keys. A pneumatic actuation is illustrated. The bellows 61, 61, one for each lever 24, are connected to levers 24 by rods 62, 62. The actuating bellows 61 may be 120 operated by means of the pumping bellows 62' illustrated as operated from motor 9. The actuation of a piano key indicated at 63 serves to depress a dowel pin 64 and thereby depress the valve 65 and open the 125 passage 66 from the bellows 61 which belongs to that particular piano key. The collapse of the bellows draws the inner end of the corresponding lever 24 downwardly and holds the same depressed so long as the 130

piano key is depressed. A quick depression and rise of the piano key will result in the production of a small hole in the paper by the corresponding punch 19, while holding 5 the key 63 depressed for a longer period will result in the production of an oblong slot in the paper, because of the continuous rapid perforation of the same by the punch 19.

10 The guideways for the vertical members 21, formed by slots 22 in bars 23, are completed by the plates or gates 67 which are secured in position against the outer surfaces of bars 23 to close the outer ends of 15 slots 22. Vertical members 21 are preferably connected with actuating levers 24 by pivot pins 68, levers 24 being provided at their inner ends with bifurcated ends 69 between which the lower ends of members 21 20 extend and in which the pivot pins 68 are mounted. Members 21 are preferably formed with slots in their sides, adjacent their lower ends, in which pins 68 engage to form the pivotal connection, gate 67, when 25 mounted in position, serving to hold members 21 in vertical position so that pins 68 will press against the inner ends of these slots. When it is desired to remove a lever 20 and its punch 19 for inspection or repair, 30 it is only necessary to unscrew the gate 67, swing the vertical member 21 upwardly between the arms 69 of lever 24, vertical members 21 swinging clear of pivot pins 68, and then lift the lever 20 so that its punch 19 35 will rise out of its guide, the lever 20 swinging about its rounded end 29 in slot 28 until the punch 19 is free from its guide. It will be noted that the fulcrums 37 of levers 20 can only move in a straight vertical line in 40 operation, because of the sliding engagement of vertical connections 21 in retaining bar 23.

The guide member 35 is preferably secured to the upper ends of the side members 45 46 of bracket 45 by means of vertical screws (not shown). It is an advantage of my construction that the upper part of the apparatus may be removed as a unit from the lower part by unscrewing the bolts which 50 extend through lugs 6 and 7 on frame members 2 and 5. When this is done the screws, just referred to, which hold guide member 35 to bracket members 46 are first unscrewed. After this a pair of clamping 55 screws 70, 70, which may be loosely mounted in the frame members 5, 5, are screwed into position to clamp guide member 35 to the frame members 5, 5. Thereupon, after unscrewing the bolts 8 which extend through 60 lugs 6 and 7 and removing the pivot pins 68 which connect vertical members 21 with actuating levers 24, the upper structure may be removed as a unit with all of the levers 20, guide members 35, punches 19, and vertical 65 members 21, mounted in position.

It will be noted that the driving mechanism for the paper feed operates from one of the eccentric shafts 15, so that a constant ratio will obtain between the rate of punch reciprocation and the rate of paper feed. 70 Because of this it follows that the punches reciprocate the same number of times per inch of paper feed, regardless of any changes in the speed of the motor or source of power, which I consider a highly desirable effect. 75

It will be obvious that my invention is not strictly limited to the exact details of construction described, but is as broad as is indicated by the accompanying claims. 80

What I claim is:—

1. In a music recorder, the combination of a plurality of levers, punches pivotally connected with said levers to extend at an angle thereto, means constituting fulcrums for said levers, guides for said punches, means arranged to constantly oscillate said levers about their fulcrums, said means having loose connections with said levers at points distant from said fulcrums permitting the levers to have endwise play in respect to said means, and means for shifting any desired one of said levers when a note is to be recorded. 90

2. In a music recorder, the combination of a plurality of levers, punches pivotally connected with said levers to extend at an angle thereto, means constituting fulcrums for said levers, guides for said punches, reciprocating means slidably connected with said levers at points distant from said fulcrums for imparting oscillation to said levers about their fulcrums, and means for shifting a desired one of said levers when a note is to be recorded. 95

3. In a music recorder, the combination of a plurality of levers, punches pivotally connected with said levers to extend at an angle thereto, means constituting fulcrums for said levers, guides for said punches, a member having slots therein in which portions of said levers distant from said fulcrums slidably engage, means for imparting reciprocation to said member, and means for shifting a desired one of said levers when a note is to be recorded. 110

4. In a music recorder, the combination of a plurality of horizontally mounted levers, vertical members pivoted thereto to constitute fulcrums therefor, guides in which said members are slidably mounted, punches pivoted to said levers to hang vertically therefrom, means slidably connected with said levers at points distant from said fulcrums for imparting oscillation to said levers about their fulcrums, and means for lowering a desired one of said vertical members in its guide when a note is to be recorded. 120

5. In a music recorder, the combination 130

of a plurality of horizontally mounted levers, vertical members pivoted thereto to constitute fulcrums therefor, a guide member formed in two sections, constituting 5 slideways for said vertical members, one of said sections being removable from the other to permit said vertical members to be swung upwardly about their pivots, punches pivoted to said levers to hang vertically therefrom, guides for said punches, means for 10 lowering a desired one of said vertical members in its slideway when a note is to be recorded, and means removably connected with said levers at points distant from their fulcrums for imparting oscillation thereto.

6. In a music recorder, the combination 15 of a plurality of horizontally mounted levers, vertical members pivoted thereto to constitute fulcrums therefor, a guide member formed in two sections, constituting slideways for said vertical members, one of said sections being removable from the other to permit said vertical members to be swung upwardly about their pivots, punches pivoted to said levers to hang vertically therefrom, means arranged to oscillate said levers, and means for lowering the fulcrums 20 of said levers when desired, comprising levers pivotally connected with the lower ends of said vertical members, the pivotal con-

nnections being arranged to permit the ready separation of said vertical members from said last named levers.

7. In a music recorder, the combination 35 of a frame, a die and means for feeding a paper strip over said die, carried by said frame, a second frame removably carried by said first frame, a plurality of levers, punches carried thereby and means for oscillating said levers, carried by said second frame, 40 guides for said punches, adapted to be secured to said second frame, means carried by said first frame for shifting desired ones of said levers, said means being removably secured to said levers, and separable power 45 connections between moving parts carried by said two frames.

8. In a music recorder, the combination 50 of a plurality of horizontally mounted levers, punches carried thereby, vertical pit-men and a bar carried thereby arranged to impart oscillation to said levers, a frame, having lugs above and below said bar, and springs between said bar and lugs.

This specification signed and witnessed 55 this 24th day of March, 1919.

PHILIP J. MEAHL.
